4 Claims. (Cl. 43—9)

This invention relates to cable sets which in use are attached to a trawl net to form the bridle assembly by which the net is towed, for example, along the sea bed. The cable set provided by the invention achieves a substantial increase in the vertical mouth opening of the net, and also includes features which facilitate hauling and shooting of the trawl, in order to reduce the period of time required to unload a catch and thereafter reset the trawl.

The cable set, according to the present invention, comprises a pair of headline legs adapted to be attached to the ends of the headline of the trawl net, a pair of groundline legs adapted to be respectively attached to the ends of the ground rope of the trawl net, a pair of link wires respectively adapted to link each headline leg to the ground rope, each link wire being attached at its upper end to its respective headline leg at a first point and at its lower end to a second point on said ground rope, there being a pair of second points on said ground rope, each second point being positioned aft of its nearest ground rope end, when the cable set is assembled and in use the arrangement is such that, during trawling, the link wires are slack but during shooting and hauling of said headline and groundline legs said link wires are tensioned by the moving of said headline legs forward relative to their respective groundline legs so that said headline legs are tensioned and thus prevented to a large extent from fouling their respective groundline legs.

A cable set or assembly constructed to operate in this way enables the satisfactory use of long headline and groundline legs, for example, of forty fathoms in length. This gives a consequential increase in the headline height obtainable during trawling, which in turn permits an increase in the vertical mouth opening of the net from the usual order of five to six feet to the order of sixteen feet, for example.

It is to be clearly understood that the invention includes both a set of cables adapted to be assembled in the way described, and also the assembled combination of cables and trawl net.

In preferred constructions, each pair of ends of the headline and groundline legs, remote from the headline and groundline attachment points and which are associated with the same side of the net are, or are adapted to be coupled to constitute in use towing points to which the trawling pull along the sea bed is applied. With this construction the headline legs at a predetermined point between the towing points and their headline attachments, are each provided with a haul attachment and these attachments are used when hauled to tension the link wires, by moving the headline legs forward relatively to the groundline legs, to apply the required load from the weight of the groundline bobbins to maintain the headline legs taut during hauling.

The preferred embodiment of the invention will now be described by way of an example with reference to the accompanying drawings in which:

FIGURE 1 shows a sectional elevation of a part of the trawl net assembly, the section being taken on the centre line of the trawl net.

2

FIGURE 2 is a view of the otter board and the headline and groundline legs.

FIGURE 3 shows an enlarged view of details at A on FIGURE 2.

FIGURE 4 shows the same parts as in FIGURE 3 but in the position they assume at the commencement of hauling in the legs or just prior to shooting of the board.

FIGURE 5 shows an enlarged view of details contained in circle B on FIGURE 1.

FIGURE 6 shows the arrangement of the gear at the forward gallows when "bang up" of the net is in progress, hauling of the headline being completed and the ground rope is in the process of being "banged up."

FIGURE 7 shows a half plan of a portion of the trawl net with the direction of travel vertically on the page.

This embodiment describes the operation of the trawl gear by the so called "bang up" system in which the ground rope is hauled into a shallow catenary, so that the ground rope bobbins can swing over the gunwale in the shooting and hauling of the trawl. The headline may or may not be hauled into a shallow catenary.

Referring to FIGURE 1, the headline of a trawl net is shown at 10, one of the headline ends is shown at 11. One ground leg 12 and one headline leg 13 are shown also. It will be appreciated that as one side of the net is being described various parts are duplicated for the other side of the gear that is not shown.

The trawl net is shown at 14 and the forward edge of the wing is shown at 15. Ground rope 16 is partly shown and a link wire 17 is connected to the headline 10 at a first point 18 and with the ground rope 16 at a second point 19. FIGURE 7 of the drawings shows how the link wire 17 is connected to a point spaced from the ends of the ground rope.

35 A Dan Leno bobbin 20 is shown connected in the ground rope 16 but the other rollers and bobbins of a typical ground rope have been omitted for clarity.

FIGURE 2 shows the otter board 23 and the towing warp 24. The backstrop 25 has a Kelly's Eye 30, at the towing point 26, which is formed by a special stopper forming the junction of the headline leg 13 and the groundline leg 12. An independent piece 27 is connected at its forward end to a point just forward of the otter board 23. The other end of the independent piece 27 is attached to a ring in the headline leg 13; this ring will hereinafter be referred to as the haul attachment 28 and it is positioned at a predetermined point on the headline leg. The arrangement of the haul attachment is best seen in the enlarged view in FIGURE 3.

50 The independent piece 27 is provided with a swivel 29 adjacent to the haul attachment 28 and the backstrop 25 is provided with a Kelly's Eye 30, which slides on the groundline leg.

In FIGURE 4 the load of the net is taken by the independent piece 27 through the haul attachment 28, the headline leg 13 and the groundline leg 12 are both taut during hauling or shooting of the headline and groundline legs.

60 In FIGURE 5 the area around the point 18 on the headline leg 13 is shown enlarged. The link wire 17 is shown in two parts, an upper first length 32 and a second length 33. The first length 32 is attached to a Kelly's Eye 34 mounted on the headline leg 13. A headline ring 35 is formed in the headline leg 13 adjacent to the point 18 and the ring 35 acts as a stop to prevent the Kelly's Eye 34 sliding aft. The lower end of the first length 32 of linkwire 17 is provided with a stop ring 36 through which the end of the second length 33 passes. Attached to the upper end of the second length 33 is a stop link 37 having a flattened link 38, the stop link 37 being too large to pass through the stop ring 36.

In FIGURE 6 the Dan Leno bobbin 20 is shown drawn up to the sheave 40 of the gallows 41. A portion of the deck is shown at 42 and also a portion of the gunwale 43. A top sheave 44 is shown attached to the top of the gallows 41 and a messenger wire 45 having a "G" link 46 at its end is shown attached to second length 33 of linkwire 17.

During trawling the trawl operates in the usual manner and the present invention has the advantage that a greater headline height is obtainable with the longer headline and groundline legs now made practicable due to the problem of fouling being largely overcome.

When hauling in the trawl both the warps 24 are hauled in until the otter boards 23 reach their respective gallows 41 and are secured thereto. The warps 24 are then slackened and disengaged from the otter boards and the hauling tension is then applied to the independent piece 27. This has the effect of moving the headline leg 13 forward relative to the groundline leg 12 by a distance approximately equal to twice the distance between the towing point 26 and the hauling attachment 28. The result of the relative movement forward of the headline leg 13 to the groundline leg 12 is that the linkwire 17 is tensioned and the headline leg 13 takes some of the load of the trawl, such that it is taut or substantially taut so that the chance of fouling of the headline leg 13 with the groundline leg 12 is greatly reduced, if not eliminated altogether. The hauling in of the legs 12 and 13 can then proceed, the Kelly's Eye 30 sliding on the groundline leg, until the first point 18 is adjacent to the sheave 40. A messenger wire 45 is passed over the top sheave 44 and its "G" link 46 is connected into the flattened link 38. As the messenger wire 45 is hauled in the second length 33 of linkwire 17 slides through the stop ring 36, and this continues until the ground rope 16 is "banged up" between the gallows, and then it may be swung over the gunwale 43. When the ground rope is swung over the gunwale 43 the cod end and parts of the end beyond the wings are accessible on the ship for release of the catch.

During shooting of the trawl the headline leg 13 and the groundline leg 12 are both drawn out through the sheave 40 and they are both taut. This tautness greatly reduces the chance of the headline leg 13 fouling the groundline leg 12.

In certain circumstances, the legs 12 and 13 may be 45 of opposite lay cable.

The distance between points 18 measured along the curve of the headline 10 is determined by the spacing between the gallows 41 of a side trawler, and the ground rope length between the Dan Leno bobbins 20. Similarly, the distance between points 19 measured along the curve of the ground rope 16 will be determined by the spacing of the gallows 41, such that the ground rope 16 may be "banged up." The position of stop ring 36 relative to headline ring 35 will depend upon the ease of access to the flattened link 38 when point 18 is at the sheave 40.

The present invention using link wires 17 to prevent fouling of the headline and groundline legs may also be used equally well with a trawl, using the quarter rope system of operation.

5 Although this invention has been described with reference to a side trawler it may also be used with a stern trawler.

Although this invention has been described with reference to a deep water trawl it is to be understood that its scope is not limited thereto, but it may be applied to any suitable trawl with headline and groundline legs.

I claim:

1. A trawl gear comprising:
a headline;
headline legs for attachment to the ends of the headline;
a ground rope;
groundline legs for attachment to the ends of the ground rope; and
a link cable attached at a point intermediate the ends of each headline leg and extending directly to the ground rope and attached thereto;
the arrangement being that during trawling, the link cables are slack, while during shooting and hauling the cables are tensioned by forward movement of the headline legs relatively to the groundline legs with the result that the headline legs are tensioned and restrained from fouling the groundline legs.

2. A trawl gear according to claim 1, in which a pair 30 of towing points are provided, each towing point being formed at the junction of the forward end of a headline leg and the forward end of its respective groundline leg.

3. A trawl gear as claimed in claim 1, in which a haul 35 attachment is provided in each headline leg at a predetermined point, said point being determined such that when said headline and groundline legs are being hauled in or shot the length along a headline from the haul attachment to said first point plus the length of said link wire is substantially equal to the length from the respective second point on the ground rope along the groundline leg to the haul attachment.

4. The trawl gear specified in claim 1 wherein each link cable comprises two parts slidably connected to one another.
